UNITED STATES PATENT OFFICE.

CHARLES N. WAGNER, OF KNOXVILLE, ILLINOIS.

ILLUMINATED SAFETY-BRACKET FOR AUTOMOBILES.

1,210,023.

Specification of Letters Patent. Patented Dec. 26, 1916.

Application filed February 7, 1916. Serial No. 76,635.

To all whom it may concern:

Be it known that I, CHARLES N. WAGNER, a citizen of the United States, and a resident of Knoxville, in the county of Knox and State of Illinois, have invented a new and useful Illuminated Safety-Bracket for Automobiles, of which the following is a specification. My invention relates to devices attachable to automobiles for the purpose of holding, illuminating, and locking the number-plate.

It is a well known fact that owing to the ease and readiness with which the number-plate may ordinarily be detached from an automobile and a false one substituted therefor, many crimes have been successfully carried out.

In view of this one of the main objects of my invention is to provide a novel illuminated, seal-locked frame or bracket into which a number-plate may with facility be placed or from which it may with equal facility be removed, but not without breakage of the seal—the latter causing detection of the criminal.

Another object is to provide novel means, entering into the construction of the bracket, for yieldingly or resiliently holding the number-plate in place and from breakage.

Still another object is to provide a transparent or semi-transparent number-plate adapted because thereof to operate in harmony with an electric lamp or other light in rear thereof.

Still another object consists in providing for the escape of any water which might collect within the bracket or frame sections or parts.

Minor objects will presently appear. Some of these will be obvious and others particularly pointed out.

In the accompanying drawings, which illustrate a preferred embodiment of my invention, Figure 1 is a rear elevation, showing my improvements as attached to an ordinary form of number-plate-carrying projection from the rear end of an automobile; Fig. 2, a perspective thereof, somewhat reduced in size, and the number-plate removed; Fig. 3, an enlarged end view, seen in the plane of the line 3—3 in Fig. 1; and Fig. 4, a transverse section, taken in the plane of the line 4—4 in Fig. 1.

Considering the drawings in detail and referring to the elements thereof by numerals, each of which is uniformly employed,

2 indicates a fragment of a rear number-plate-carrying projection or arm of an automobile, provided with slots 3, 3.

4, 4 indicate bracket-supporting arms provided each with a slot 5, the adjacent pairs of slots 3 and 5 adapted to register. 6, 6 indicate bolts passed each through a registering pair of said slots, and 7, 7 designate nuts, one on each of said bolts, for an evident purpose.

8 indicates the back of my improved bracket 9—the word "back" as just used, being indicative of the detached bracket but not of the bracket when it is applied to the car. I prefer to construct the main elements of the frame of said bracket from a single piece of sheet metal, of which 10 is the bottom, 11 an open or skeleton front, and 12 a top having a lip 13 overlying the upper edge of said front.

14, 14' designate the ends, the latter secured to each of the portions 8, 10, 11, 12 and 13, but the former to the portions 8, 10 and 12 only. The back 8 is secured to 30 the arms 4 by rivets 15 or in any other suitable manner.

16 designates a strip of felt or other yielding material secured in any suitable manner along the angle formed by the back 8 and top 12. Extending from end to end (14, 14') I place a preferably resilient metallic guide-strip 17, secured to the bottom 10 as by rivets 18, provided with a longitudinally arranged shoulder 19 and affording, together with the lower edge of the front 11, a channel 20, through which latter any water passing over the number-plate 21 (presently more fully described) and running between the latter and said front 25 11 may escape. Said plate 21 is preferably of a transparent or semi-transparent nature, as, for instance, of glass upon which may be painted or stained, or of metal through which openings may be cut, or of any other material whereby in any manner may be displayed any symbol, sign or character desired—these of course depending upon circumstances—in order that any suitable illuminating agent, such as an electric 100 lamp 22, may cause light to penetrate the plate. The plate preferably rests upon the shoulder 19 of the strip 17 and its lower edge is held yieldingly and resiliently there-

by against the lower portion of the front 11. 110 The upper edge of the plate is held yieldingly by the guide-strip 16 against the upper

portion of said front 11. The lower edge of the plate is therefore adapted to slide between the guide 17 and the lower portions of the front 11 and its upper edge to slide 5 between the guide-strip 16 and the upper portions of said front, as indicated in Fig. 1, and it is of such length that when pushed into the position shown by full lines in said figure a seal-pin 23 which passes through 10 registering apertures in the back 8 and front 11 may be positioned as just recited and as shown best in Fig. 3, to lock said plate in place. Any character of seal, such as a car-seal 24, may be employed to engage the seal-pin 23.

It has not been thought either necessary or best to encumber this specification and drawings with descriptions and illustrations of modifications which are neither essential 15

to nor form any part of the invention herein 20 claimed. In fact, it is apparent without such that numerous details in the details of construction will present themselves to any skilled mechanic.

Therefore, without limiting myself to precise details I claim as new the following, 25 to-wit:

In a device of the nature described, a frame including a back, an open front, and a bottom; a transparent number-plate arranged in rear of said front; a spring guide-strip having a shelf-like portion on which the number plate rests, resilient means for holding the top of the plate in position, and means for illuminating said plate. 30

In testimony whereof I hereunto affix my signature this 28th day of January, 1916.

CHARLES N. WAGHER. 35
